DESIGN FOR A COMBINATION EYE CUP BASE AND COVER

Benjamin F. Conner, West Hartford, Conn., assignor to Colt's Patent Fire Arms Manufacturing Company, Hartford, Conn., a corporation of Connecticut

Application February 5, 1937, Serial No. 67,478

Term of patent 14 years

To all whom it may concern:

Be it known that I, Benjamin F. Conner, a citizen of the United States, residing at West Hartford, in the county of Hartford and State of Connecticut, have invented a new, original and ornamental Design for a Combination Eye Cup Base and Cover, of which the following is a specification, reference being had to the accompanying drawing, forming part thereof.

Of the drawing:

Fig. 1 is a plan view of a combination eye cup base and cover embodying my new design.

Fig. 2 is a front view thereof,

Fig. 3 is an end view thereof.

The stippled and unstippled portions of the drawing are intended to represent differing colors, but not any particular colors.

I claim:

The ornamental design for a combination eye cup base and cover as shown and described.

BENJAMIN F. CONNER.
